TOY MOVIES DEVICE

Alwyn R. Bunting, Portsmouth, Va.

Application August 13, 1937, Serial No. 159,004

3 Claims. (Cl. 46—56)

The invention relates to a toy movies device and more especially to a windmill acting moving picture toy.

The primary object of the invention is the provision of a toy of this character, wherein through the use of a blow pipe and a frame a rotor held within the frame can be set in motion or rotated through air currents delivered by said pipe and in this fashion a group of pictures reasonably held or carried by the rotor will create the illusion that the object or objects or the entire picture representation is in motion so that movies will be displayed in this fashion.

Another object of the invention is the provision of a toy of this character, wherein the rotor involves a pair of disks, these being channeled or grooved so that a group or series of picture holders or picture panels on interfitting thereof can be separably secured in the grooves or channels and in this way effecting a windmill for movies display of the pictures on the panels; thus the pictures can be altered or changed at the will of the operator or user of the toy.

25 A further object of the invention is the provision of a toy of this character, wherein the assembly of its parts is entirely novel and when operated will effect animated or moving characteristics to the displayed pictures.

30 A still further object of the invention is the provision of a toy of this character, which is simple in construction, thoroughly reliable and effective in operation, light in weight yet strong, durable, and inexpensive to manufacture.

35 With these and other objects in view, the invention consists in the features of construction, combination and arrangement of parts as will be hereinafter more fully described, illustrated in the accompanying drawing, which discloses 40 the preferred embodiment of the invention and pointed out in the claims hereunto appended.

In the accompanying drawing:

Figure 1 is a perspective view of the toy constructed in accordance with the invention.

45 Figure 2 is an elevation of one of the picture panels of the rotor.

Figure 3 is a view similar to Figure 2 showing another of the picture panels.

50 Figure 4 is an inside elevation of one of the rotor disks.

Figure 5 is an edge view thereof.

Figure 6 is a fragmentary detail sectional view taken horizontally and transversely to the rotor.

55 Figure 7 is a side elevation partly in section

showing by dot and dash lines the rotary travel of the rotor for movie display of the pictures.

Similar reference characters indicate corresponding parts throughout the several views in the drawing.

Referring to the drawing in detail, the toy or device comprises an open wire frame 10 preferably of rectangular shape and affords a stand having at its bottom and corners thereof extended feet 11. Within this frame is a rotor comprising a pair of spaced end disks 12, each having in the inner face thereof crossed grooves or channels 13 which open through the periphery and the said inner faces are at right angles to each other while fitted centrally in the outer faces of said disks 12 are pin stud axles 14, these rotatably received in bearing seats 15 struck from the top side members 16 centrally thereof of the frame 10. The bearing seats are struck downwardly and inwardly, the inward disposition being for the purpose of keeping the disks 12 of the rotor clear of the frame 10 at opposite sides thereof to minimize friction and also maintains the panels, hereinafter described, seated in the grooves 13 in the said disks 12.

Releasably insertable in the grooves or channels 13 in the disks 12 are the outer longer edges of crossed interfitted separable panels 17, the crossed interfitting of these being had by the slots 18 formed transversely and centrally of said panels and extending substantially one-half of the width thereof and such panels when interfitting with each other and engaged with the disks form a paddled or bladed wind wheel while created upon said panels are pictorial representations 19, these in progressive relationship being of different posture or setting so that when the wind wheel rotates clockwise these pictures or representations 19 effect animated or moving illusions imitative of movies.

The pin stud axles 14 are held in the seats by spring snap latches 20 fitting the side members 16 of the frame 10 and are freely rotatable and separably held in the seats 15.

The frame 10 has the side members 16 thereof extended and soldered or otherwise made secure to a blow pipe 21 having at its outer end a mouth piece 22, the pipe 21 being inwardly inclined toward the wind wheel and when an air current is passed through the pipe 21 or the latter blown by the user of the toy the said air current will force the wind wheel to rotate clockwise for rotary action of said wind wheel and through rapidity of rotation gives the representations 19

on the panels or paddles 17 an animated or moving picture effect.

It is preferable to have the panels or paddles 17 colored dark as at 23 about the representations 19 for assuring better concentration on the representations when the toy is in use and operated.

The longer edges of the panels 17 are recessed at 24 intermediate thereof for the interfitting of the disks 12 to avoid displacement of said panels 10 in their association with the disks in the erection of the wind wheel.

The latches 20 are such as to permit the axles 14 to be releasably held in the seats 15 and the pipe 21 gives an air impact against the paddles 15 of the wind wheel for the rotation of the same.

The panels 17 are separably interlocked with each other and similarly the panels 17 are interlocked with the disks 12.

The panels carry markings 25 which function 20 as guides in the proper assembly thereof with each other and also with the disks 12 so that the representations 19 on display will follow each other in their proper order upon rotation of the wind wheel.

25 One of the panels 17 is of greater length than the other panel and is so seated in the grooves 18 in the disks 12 so that the rotor will be weighted at one side and in this manner a starting position of such rotor will be had to receive air 30 from the pipe 21 at the start of the revolving operation or, in other words, the rotor is slightly overbalanced due to the length of one panel and the eccentric disposition thereof with respect to the other panel of the rotor.

35 It is also understood that the disks are suit-

ably colored dark congruous with the dark colored panels of the wind wheel.

What is claimed is:

1. A toy of the kind described comprising a frame-carrying blow pipe, spaced journaling disks 6 removably fitting the frame of said pipe, and crossed separably interfitted panels between the disks and detachably engaged therewith with the panels extended beyond the same and in the path of air blown through the blow pipe for the turning 10 of said panels in a rotary direction.

2. A toy of the kind described comprising a frame-carrying blow pipe, spaced journaling disks removably fitting the frame of said pipe, and crossed separably interfitted panels between the 15 disks and detachably engaged therewith with the panels extended beyond the same and in the path of air blown through the blow pipe for the turning of said panels in a rotary direction, the said panels 20 at their edges next to the disks being recessed for the seating of the said disks therein.

3. A toy of the kind described comprising a frame-carrying blow pipe, spaced journaling disks removably fitting the frame of said pipe, crossed 25 separably interfitted panels between the disks and 25 detachably engaged therewith with the panels extended beyond the same and in the path of air blown through the blow pipe for the turning of said panels in a rotary direction, the said panels at their edges next to the disks being recessed for 30 the seating of the said disks therein, and means formed on the frame of the said blow pipe for action upon the disks to hold the same fitted with the said panels.
